UNITED STATES PATENT OFFICE.

HENRI VIRY, OF RAMBERVILLE, FRANCE.

POCKET TYPE-WRITER.

1,037,564.

Specification of Letters Patent.

Patented Sept. 3, 1912.

Application filed May 23, 1912. Serial No. 699,104.

To all whom it may concern:

Be it known that I, HENRI VIRY, a citizen of France, residing at Route St. Gorgon, Ramberville, France, have invented a new and Improved Pocket Type-Writer, of which the following is a specification.

This invention relates to a pocket typewriter of the kind wherein there is provided a type wheel that can be raised and depressed and wherein the types are arranged at the ends of radially extending arms of an adjustable disk.

In typewriters of this kind, as heretofore constructed, it has been necessary either to use both hands to produce the type-impressions, or the type wheel has not been capable of making a complete revolution. The former of these defects is especially disadvantageous when the typewriter is used during a journey, as one hand is then required to hold the machine; while the latter defect necessitates the constant reciprocation of the type wheel, with the result that it has frequently to be rotated through a much larger angle than would be necessary were it continuously rotatable. Now by means of the present invention both of these defects are obviated with the result that a pocket typewriter in accordance with this invention is adapted to serve as a standard machine free from all such defects. These advantages are secured by means of an arrangement wherein, whenever the type wheel is depressed, a lever connected with the bed-plate is also depressed and by this means simultaneously depresses that arm of the type wheel, which is adjusted beneath it; while simultaneously with the depression of the wheel and the downward movement of the lever there is brought into operation a ratchet gear which arrests the disk to which the types are attached and adjusts it in such manner that the impression of the type on the paper is produced exactly in the right place.

A typewriter according to the present invention possesses the further advantage that the paper feed mechanism is very considerably simplified.

The accompanying drawings illustrate apparatus in accordance with this invention; wherein—

Figure 1 is a plan of the typewriter viewed from above; Fig. 2 is a side elevation of the entire apparatus; Fig. 3 is a section on the line A—B of Fig. 1; Fig. 4 is a

section on the line C—D of Fig. 1 and Fig. 5 is a plan of the type wheel.

The typewriter comprises a bed-plate or support 1 to which there is hinged a plate 2 which can be raised or depressed, and which carries the type mechanism. On the end of the bed-plate 1 opposite to that at which the plate 2 is hinged, there is arranged a lever 3 by means of a hinge 27. The typewriter can be held in the left hand by means of a bent handle 16. To the lower face of the plate 2 there is attached the type wheel 7 shown in Fig. 5, having its circumferential portion divided into arms or fingers to the lower face of which are attached the types preferably made of rubber. One arm is cut away to enable the lever 3, when the machine is collapsed, to occupy the gap thus formed. The type wheel 7 is rotated by means of a knob 18, which serves also as the axis of the wheel 7 and which carries an indicator 14 which moves over a stationary disk 19 that is rigidly connected with the plate 2, and has engraved on it representations of the characters to be imprinted. By rotating the indicator 14 rigidly connected with the rotatable type wheel 7 over the plate 2, any desired character on the type wheel can be brought into printing position. Beneath the stationary disk 19 secured to the plate 2 there is mounted on the shaft of knob 18, so as to be rigidly connected with the wheel 7 and the indicator 14 a spur wheel 6, provided, as shown in Fig. 1, with teeth of considerable depth, by means of which the position of the adjusting disk 6 can be corrected if, when the lever 3 is depressed, the adjustment has not been accurately effected, the manner in which this is effected being hereinafter more fully described. The rubber types on the wheel 7 are inked by means of an annular inkpad 15 against which the entire type wheel is pressed when the plate 2 is depressed. The inkpad has a portion cut away at the place at which the lever 3 depresses the type of which an impression is to be produced.

The lever 3 which, as already stated, is connected with the bed-plate 1 by means of the hinge 27, is provided with a slot *a* with which there engages a pin *m* on the plate 2, thus insuring that when the plate 2 and the type wheel 7 are depressed, the lever 3 will also be depressed and passing through a slot in the plate 2, will press against that arm of the type wheel 7 which has just been

adjusted to printing position. The lever 3 is connected by means of a link 4 with a slide 23 that is guided on the plate 2 in such manner that when this plate, together with the lever 3, is depressed, the slide 23 is moved to the right. The slide 23 is provided with a pointed projecting end which is guided between two studs 20 on the plate 2. When the slide is moved forward this projecting end is forced against the teeth of the spur wheel 6 already mentioned with the result that, if the type is not quite accurately adjusted, the pointed end of the slide 23 will move the spur wheel 6 some-
what to the right or left, as may be required, and thus bring about the accurate adjustment of the type-wheel 7 before the desired impression is obtained.

Fig. 3 illustrates the paper feeding mechanism. To the sides of the plate 2 there are pivoted at 22 a pair of lever-arms 8 that bear against hooks 11 on a slide 10 that is subject to the action of tension springs 12, and is movable in guides 24 and 24' arranged in the plate 1. To the end of the slide 10 is attached a shackle or dog 9 that terminates in a detent 21 and a projection 25. The detent 21 passes through the plate 1 and engages with apertures 26 in the carriage 13 located beneath the bed-plate 1. When now the plate 2 is depressed for the purpose of securing an imprint, the levers 8, by means of the hooks 11 move the slide 10 to the left in the guides 24 and 24' with the result that the detent 21 carries the carriage 13 to the left until the projection 25 comes in contact with the guide 24', and by this means turns the shackle 9 upward and thus removes the detent 21 out of the apertures 26 of the carriage 13 and

so arrests its further forward movement. The transverse movement of the paper carrier 13 is effected in the well-known manner by means of a roller.

What I claim is:—

1. A pocket typewriter comprising a support, a plate hinged thereto, a wheel rotatably secured to said plate at the lower side thereof, said wheel being provided with a plurality of radially extending fingers, types on the lower faces of said fingers, a slotted lever fulcrumed to the support, and a pin on the plate that engages the lever-slot, whereby a depression of the plate effects an engagement between the lever and the underlying finger to print the type carried by said last named finger. 45

2. A pocket typewriter comprising a type wheel which can be raised and depressed; types that are attached to radially extending arms of the type wheel; an adjusting device and an adjusting disk (6) connected with the type wheel, the adjusting disk being provided with pointed teeth which effect the arrest and accurate adjustment of the type wheel; and a lever, which is connected with the bed-plate, is provided with a guide-slot, and the end of which is adapted, upon the depression of the type wheel to bear against the type adjusted to printing position and thus to cause an impression to be produced on the paper, whereupon the lever pushes forward a slide provided with a pointed termination adapted to pass between the teeth of the said adjusting disk (6). 60 65 70 75

HENRI VIRY.
